UNITED STATES PATENT OFFICE

JOSEPH SCHMALZL, OF BETHLEHEM, PENNSYLVANIA

NONSKID CHAIN

Application filed April 20, 1931. Serial No. 531,543.

This invention aims to provide a non-skid cross chain for anti-skidding devices of the kind used on automobile tires, the constituent links of the chain being so made that they will afford an efficient road-grip, be capable of long continued use, and afford a means whereby repairs can be made readily, certain parts of the links protecting other portions of the links from wear, and also providing the afore-10 said road-grip.

A preferred form has been shown, but a chain maker, working within the scope of what is claimed, can make alterations in that form, without departing from the spirit of 15 the invention.

In the drawings:

Figure 1 shows, in section, a tire casing on which has been mounted a cross chain constructed in accordance with the invention; 20 Figure 2 is a top plan showing a portion of the chain; Figure 3 is a top plan showing a portion of the chain, the links having been concatenated in a manner differing slightly from the disclosure of Figure 2; Figure 4 is 25 an elevation of one link, the fingers being spaced apart, and shown as they will appear before they are brought together to make the complete chain; Figure 5 is an elevation showing the fingers spaced apart by bending the 30 links in a manner differing slightly from the disclosure of Figure 4.

There is provided a metal link for non-skid cross-chains, comprising a main bar 1 provided at one end with a convexed support 2 merging into one end member 3 of the link, said end member 3 merging into a second convexed support 4 provided with a finger 5. The opposite end of the main bar 1 merges into the opposite end member 6 of the link, 35 said opposite end member 6 of the link merging into a third convexed support 7 provided with a finger 8. All of the said supports 2-4-7 are located in approximately the same plane A-B of Figure 4 represented by the outer surface of the tire casing 15. The fingers 5 and 8 are approximately parallel, close together, and approximately at right angles to the said plane A-B. The first-specified end member 3 curves away from the 40 plane A-B, as shown at 10, and the main

bar 1 slants away from said plane, to cause the second-specified end member 6 to slant, as at 12, away from said plane, the aforesaid slant of the main bar being designated by the 45 numeral 11.

The link above described is characterized by the fact that the fingers 5 and 8 project away from the plane A-B, beyond all other 50 portions of the link, to lessen the wear on said portions of the link, and to form a road-grip.

The non-skid cross-chain embodies a plurality of links, constructed as hereinbefore set forth, and concatenated end to end, as in 55 Figure 2, the fingers 8 and 5 of all of said links being arranged substantially in a straight line, longitudinally of the chain.

In Figure 3, parts hereinbefore described have been designated by numerals previously used, with the suffix "b". In Figure 3, the 60 links are concatenated end to end, as in Figure 2, but the fingers 8b-5b of some of the links are disposed at one side of the chain, the fingers of others of the links being disposed at the opposite side of the chain, to 65 form two substantially straight lines of fingers extended longitudinally of the chain. The operator can assemble the links and in Figure 2, or as in Figure 3, depending upon his desires.

The link, when open, appears as in Figure 4, and is fashioned from a single bar of material, provided at its extremities with the fingers 5 and 8, which, in the completed chain, are brought close enough together to prevent 70 one link from becoming detached accidentally from a like link, the fingers projecting in a direction substantially at right angles to that portion of the link whereon the link is supported when in use.

As a matter of practice, the inner edges of the fingers 5 and 8 may be brought into contact, as at 16, whereby one finger will brace and reinforce the other.

The link in its open form, shown in Figure 75 4, may be used as a repair link: or, if the operator prefers, he can form the link, either as a repair link, or as a link in the complete chain, as disclosed in Figure 5. In Figure 5, parts hereinbefore described have been desig- 80 85 90 95 100

nated by numerals previously used, with the suffix "a". The part 4a of the link is bent upwardly, and the space between the fingers 8a and 5a is such that when the link is used on the road, the pressure of the surface of the road on the finger 5a will bring it down into the position of the finger 5 of Figure 1.

As the vehicle wheels turn, one line of fingers 5-8 in Figure 2, or two lines of fingers 10 5b-8b in Figure 3, in each cross-chain, will come into contact with the roadway and afford a sure, non-skid grip; and because the fingers project as hereinbefore specified, wear on the links will be confined largely to the fingers, 15 the wear on the remaining portions of each link being cut down. The link is made of a good grade of metal, preferably steel, and the fingers 5 and 8 do not tend to bend or broom out at their ends. Rather, they wear 20 away evenly and fairly, and may be described as being self-sharpening.

Any known means 14 may be provided for holding the cross-chain on the tire casing 15, as in Figure 1.

25 Having thus described the invention, what is claimed is:

1. A link for non-skid cross-chains, comprising a main bar provided at one end with a convexed support merging into one end member of the link, said end member merging into a second convexed support provided with a finger, the opposite end of the main bar merging into the opposite end member of the link, said opposite end member of the link 35 merging into a third convexed support provided with a finger, all of said supports being located at approximately the same plane, the fingers being approximately parallel, close together, and approximately at right angles to said plane, the first-specified end member curving away from said plane, and the main bar slanting away from said plane, to cause the second-specified end member to slant away from said plane.

40 2. The link for non-skid cross-chains of claim 1, further characterized by the fact that the fingers project away from said plane, beyond all other portions of the link, to lessen the wear on said portions of the link, and to 45 form a road-grip.

3. A non-skid cross-chain embodying a plurality of links, constructed as set forth in claim 1, and concatenated end to end, the fingers of all of said links being arranged substantially in a straight-line, longitudinally of the chain.

4. A non-skid cross-chain embodying a plurality of links constructed as set forth in claim 1, and concatenated end to end, the fingers of some of the links being disposed at one side of the chain, and the fingers of others of the links being disposed at the opposite side of the chain, to form two substantially straight lines of fingers extended longitudinally of the chain.

5. A substantially O-shaped link for non-skid cross-chains, fashioned from a single bar of material, the bar being provided at its ends with fingers located at one side of the link and intermediate the ends of the link, the fingers being located closely enough together to hold one link concatenated with another link, the link having three points of support, two of which are located below and closely adjacent to the fingers, the third point of support being located at the opposite side of the link and closely adjacent to one end of the link, the fingers being disposed substantially at right angles to the plane formed by said three points of support.

In testimony that I claim the foregoing as my own, I have hereto affixed my signature.

JOSEPH SCHMALZL.
